JULIEN BERGE, OF TIRLEMONT, BELGIUM, ASSIGNOR TO RAFFINERIE TIRLEMONTOISE
SOCIÉTÉ ANONYME, OF TIRLEMONT, BELGIUM, A CORPORATION

PROCESS FOR DECOLORING SUGAR CRYSTALS

No Drawing. Application filed February 11, 1927, Serial No. 167,601, and in Germany September 30, 1926.

In masscuite, more particularly in raw sugar, even after exposure to centrifugal action, certain colouring constituents which, apparently, are enclosed in the outer layers 5 of the crystals, still remain adhering to the crystals and, therefore, after washing can only be removed in a centrifuge, the outer crystal layers being dissolved and separated by centrifugal force. This involves, however, a loss in the yield of crystal.

The invention consists in a process for removing the colouring constituents, so that this loss of crystals is avoided. The sugar crystals, freed as far as possible from the 15 adhering mother liquor by centrifugal action (for instance by the use of washing liquid in the centrifuge or a particularly high centrifugal force such as disclosed in my co-pending application, Serial No. 167,598, filed 20 concurrently herewith which has resulted in Patent No. 1,775,385,) but not quite colourless, are mashed with a saturated or approximately saturated pure white sugar solution. The coloured constituents of the crystals pass 25 then completely or almost completely according to the duration of the mashing process into the sugar solution without the crystals, as such, being attacked. At the end of the mashing process the sugar solution is as far 30 as possible completely freed from the crystal in any suitable manner, for example by exhaustion or centrifugal action. The dyes taken up by the sugar solution can in known manner be again removed from the solution 35 by filtering through animal charcoal, decolorizing charcoal or the like, and can again be used for mashing the crystals. If the dyes are not sufficiently removed from the crystals by a single mashing this can be repeated with 40 a fresh sugar solution.

I claim:

1. A process for removing coloring matter from sugar crystals by means of a pure white sugar solution without substantial loss of crystallized sugar and in which said solution is maintained in a condition in which it is adapted to be regenerated by passing it through a filter of the charcoal type, comprising first completely freeing the sugar crystals 45 from mother liquor, then mashing said sugar

crystals with a pure white sugar solution to remove the coloring matter from said sugar crystals, said coloring matter passing into said solution, then separating said color bearing solution from said crystals and maintaining said separated solution in a condition in which it may be regenerated by passing it through a filter of the charcoal type. 55

2. A process for removing coloring matter from sugar crystals by means of a pure white sugar solution without substantial loss of crystallized sugar and for maintaining said solution in a condition in which it is adapted to be regenerated by passing it through a filter of the charcoal type, comprising first 60 completely freeing the sugar crystals from mother liquor, then mashing said sugar crystals with a pure white sugar solution to remove the coloring matter from said sugar crystals, said coloring matter passing into 65 said solution, separating said color bearing solution from said crystals, and regenerating said solution by passing the same through a filter of the charcoal type. 70

In testimony whereof I have affixed my signature. 75

JULIEN BERGE.
